UNITED STATES PATENT OFFICE.

JOHN L. COPP, OF ROCHESTER, NEW HAMPSHIRE.

UNDER-VEST.

SPECIFICATION forming part of Letters Patent No. 236,989, dated January 25, 1881.

Application filed September 29, 1880. (Model.)

To all whom it may concern:

Be it known that I, JOHN L. COPP, of Rochester, in the county of Strafford and State of New Hampshire, have invented a new and valuable Improvement in Under-Vests; and I do hereby declare that the following is a full, clear, and exact description of the construction and operation of the same, reference being had to the annexed drawings, making a part of this specification, and to the letters and figures of reference marked thereon.

Figure 1 of the drawings is a representation of the device applied to the wearer. Fig. 2 is a central vertical section. Fig. 3 is a view of one of the re-enforcing pieces. Fig. 4 is a view of the front section. Fig. 5 is a view of the back section.

This invention relates to devices for the protection of persons, whereby they are prevented from taking cold.

The invention consists in a garment of peculiar construction to take the place of or supplement the ordinary undershirt.

In the drawings hereto annexed, A represents the front, and B the back, section of a garment, each constructed like the other, except that the edges of the back section overlap those of the front, or the reverse. If desired, the two sections may be made in one piece, 30 with arm-holes. The outside or re-enforcing pieces, C and D, are made smaller than the sections A and B and of different shape, and are firmly attached to said sections. One section fits the back, the other the chest, so as to

bring the smaller pieces C and D over the 35 vital organs.

The edges of the two sections A and B may be fastened by buttons, tape, or an elastic strap, as desired.

This garment is made of wool or any desired material, and forms a warm and comfortably-fitting wrap, which in cold weather protects the wearer from cold and renders him less liable to disease.

I am aware that a chest-protecting vest has 45 been used; but in that case a regular vest was constructed, and connected chest and back protectors were secured thereto by hooks and eyes and buttons, as may be seen in Patent No. 200,063, February 5, 1878. This construction I do not claim, but desire to limit myself to the construction herein shown and described.

Having thus described my invention, what I claim, and desire to secure by Letters Patent, 55 is—

An under-vest, substantially as described, the section A having re-enforcing piece C, in combination with section B, having re-enforcing piece D, the two sections buttoned together 60 at the shoulders and sides.

In testimony that I claim the above I have hereunto subscribed my name in the presence of two witnesses.

JOHN L. COPP.
